STARTER DRIVE FOR AUTOMOBILE
ENGINES OR THE LIKE

William O. Rose, Wyandotte, Mich., assignor of
one-eighth to Roy C. Mercer, one-eighth to
William B. Fisher, and one-eighth to Regina
Koepfle, all of Wyandotte, Mich.

Application June 15, 1935, Serial No. 26,761

5 Claims. (Cl. 74—7)

The present invention pertains to a novel starter drive for automobile engines or the like, particularly the electrically operated mechanical starter for the gasoline motor in an automobile, 5 truck or tractor. The device is also useful in connection with stationary and other engines that must be turned over in starting.

The general object of the invention is to eliminate some of the defects of the conventional or 10 Bendix starter and to improve the operation of the starter in other respects. In the conventional starter, the starter gear travels on a threaded sleeve towards the fly wheel gear. In order to prevent travel of the gear along the 15 sleeve under vibration, the gear has a weight fixed thereto, usually in the form of a segment of metal unbalanced with respect to the center of rotation. This weight also determines the rest or idle position of the starter gear. The gear 20 also has a drag pin engaging the threaded sleeve for further resisting movement of the gear under vibration.

One of the difficulties with the conventional starter is that the electric starting motor, and 25 hence the starter gear, acquires a high speed by the time the starter gear meshes with the fly wheel gear, thereby imposing a high torque and strain on the starter assembly as the gears come into mesh. This high speed is developed 30 while the starter gear travels along a rather long threaded sleeve which is given extra length to permit the starter gear to travel a given distance until its off-center weight comes to the bottom position, without the gear interfering with 35 the fly wheel gear.

This objection and others incidental thereto, which will be described below, is overcome in the present invention by means of a free or floating weight, rather than a fixed weight, associated with the starter gear. According to the 40 invention, the starter gear is formed with a chamber containing a mobile weight such as mercury adapted to find its bottom position by a movement independent of that of the starter gear itself. Consequently, the weight comes to 45 its bottom position without necessitating travel of the starter gear along the threaded sleeve, and the sleeve may therefore be shortened to the extent ordinarily allowed for travel under 50 the influence of the usual fixed weight. The speed of the starter gear at the time of mesh with the fly wheel gear is correspondingly reduced, and the strains incidental to high speed 55 meshing are also reduced. The previously men-

tioned chamber is preferably formed with a baffle that prevents splashing of the mercury.

Another characteristic of the invention is the provision of a tension spring in place of the usual torsion spring. The latter places certain 5 parts of the assembly under strains which are avoided by the use of a compression spring.

In connection with the compression spring, the 10 starter gear is limited in its movement towards the fly wheel gear by a rotatable stop rather than the usual fixed stop. On engaging the rotatable stop, the starter gear is free to continue 15 in rotation even though the fly wheel gear has not yet moved. In this interval, the rotating starter gear cannot advance further on its 20 threaded sleeve and consequently moves the sleeve back on its shaft, thereby compressing the spring to a pressure corresponding to the load in and on the motor up to the time of turning over.

The invention is fully disclosed by way of example in the following description and in the 25 accompanying drawing in which

Figure 1 is a side elevation of the device;

Figure 2 is a section on the line 2—2 of Figure 1;

Figure 3 is a section on the line 3—3 of Figure 2, and

Figure 4 is an elevation of the baffle ring.

Reference to these views will now be made by 30 use of like characters which are employed to designate corresponding parts throughout.

The numeral 1 designates the starter drive shaft which is usually a prolongation of the shaft 35 of the electric starting motor. The shaft carries a threaded sleeve 2, the forward end of which abuts a taper roller bearing 3 on the shaft 1. At the rear end of the sleeve 2 is formed a housing 4 spaced from the shaft 1 and having one or more outwardly extending lugs 5. Adjacent 40 to the member 4 is another housing 6 having its wall spaced from the shaft 1 and formed with a boss 7 journaled on the shaft and secured thereto by a key 8. A split ring 9 is fitted in grooves 10 formed in the shaft 1 and boss 7 45 to prevent the member 6 from shifting lengthwise on the shaft, while the key 8 causes the member 6 to turn with the shaft as will be described more fully below. The outer housing 6 has lengthwise slots 11 in its wall slidably receiving the ears 5. Within the housings 4 and 6 is mounted a coil spring 12 surrounding the shaft 1 and having its ends bearing against these parts. This is the main or take-up spring of the 50 device and replaces the torsion spring of the 55

conventional starter drive. Obviously, the spring 12 is positioned before assembling the housing 6 and locking it on the shaft.

The starter gear 13 is mounted on the threaded sleeve 2 and has internal threads 14 meshing with those of the sleeve. The rear end of the gear 13 has its diameter enlarged as indicated by the numeral 15, and at this end is formed an annular cavity 16 which is sealed by a flat ring 17 suitably secured in the enlarged end of the gear. The cavity or chamber 16 contains a mobile balanced weight consisting preferably of a quantity of mercury 18 or any other suitable substance, as distinguished from the usual fixed weight in the form of an enlarged segment on the gear. To prevent excessive splashing and whirling of the mercury in the operation of the device, a baffle ring is fitted in the chamber 16 as shown in Figures 2, 3 and 4. This member is in the nature of a polygon having its vertices 19 engaging the outer wall of the chamber and its sides concaved towards the inner wall of the chamber as indicated by the numeral 20. The pockets thus formed between the sides of the polygon and the outer wall of the chamber 16 are placed in communication with one another by means of ports 21 formed in the vertices without establishing communication to the interior of the polygon. The mercury is of course contained in the outer pockets as shown in Figures 2 and 3. On the forward end of the housing 4 is slidably mounted a gear retaining sleeve 22 engaging the ring 17 when the starter gear 13 is in the retracted position. The sleeve 22 has an internal shoulder 23 which at this time bears against a stop ring 24 fitted in the wall of the housing 4. The exposed outer wall of the housing 4 is surrounded by a cushion spring 25 bearing against the rear end of sleeve 22 and a shoulder 26 on the rear end of the housing 4. This spring is considerably lighter than the take-up spring 12 and is under compression to hold the sleeve 22 against the gear 13 for a purpose presently to be described.

In the operation of the device, the shaft 1 is turned by an electric motor, whereupon the housings 6 and 4 are also turned, together with the threaded sleeve 2, whereby the starter gear 13 is advanced on the sleeve in the usual manner. It has been observed in actual operation that the gear 13 is so well balanced by the mobile weight 18 therein that it does not rotate while advancing on the threaded sleeve 2. The forward movement of the starter gear is limited by the engagement of a stop shoulder 27 on its forward end with the outer race 28 of the taper roller bearing 3.

At this time the starter gear 13 comes into mesh with the flywheel gear in the usual manner, and as the shaft 1 continues in rotation, it turns the gear 13 and with it the flywheel gear to turn the motor over. Inasmuch as the gear 13 turns freely against the bearing 3 but can now no longer advance on the threaded sleeve 2, the sleeve must slide back on the shaft 1, thereby compressing the take-up spring 12 against the non-rotating housing 6. The final compression of the spring 12 varies according to the work necessary in turning over the motor or, in other words, the load on and in the motor.

When the motor begins to fire, the flywheel gear speed exceeds that of the starter gear 13 and thus throws the gear 13 back on the threaded sleeve 2 in the usual manner. The ring 17, which may be considered a part of the gear 13, strikes

the retaining sleeve 22 and compresses the spring 25 somewhat. The mobile weight 18 comes to its bottom position without necessitating rotation of the gear 13 on the sleeve 2, as a result of which the compressed spring 25 exerts a pressure against the gear 13 through the slidable retaining sleeve 22. This pressure binds the gear 13 against the walls of the threads of the sleeve 2 sufficiently to resist slipping of the gear under ordinary vibration on a down grade, but not enough to impede movement of the gear in the starting operation previously described.

The previously mentioned balancing of the gear 13 without lengthwise movement, because of the mobile or floating balanced weight, enables the use of a shorter threaded sleeve than usual. Further, the lengthwise pressure exerted by the cushion spring 25 on the gear 13 and against the threads of the sleeve 2 does away with the need of the usual drag pin to resist shifting of the starter gear under vibration. These two characteristics of the invention eliminate excessive high speed of the starting motor and starter gear 13 when coming into mesh with the flywheel gear, which excessive speed is common and objectionable in the conventional starters, although unavoidable, for the reasons already set forth. Moreover, the substitution of a compression spring for the usual torsion spring does away with the strains and breakage that occur at the parts where the torsion spring is anchored.

The stoppage of the starter gear 13 against the bearing race 28 provides a smoother, more efficient and less destructive action than when this gear strikes against a fixed collar, as in the conventional devices. Further advantages of the present invention are the avoidance of breakage of the main spring on back firing of the motor and sticking of the starter gear against the flywheel.

The advantages of the invention may be further summarized as follows:

1. The starter gear can not be heard when meshing with the flywheel gear because the short sleeve on which the starter gear travels does not permit excessive speed of the starting motor and the starter gear prior to meshing.

2. The short sleeve need not have a stop fixed thereto, because of the fact that the main take-up spring equalizes the shock of the load and thus acts as a shock absorber.

3. The starter gear is retracted to its neutral position by the force of the main spring in expanding to neutral position. The compression of the spring occurs after the starter gear strikes the rolling stop 28, accompanied by movement of the sleeve into the housing 6. Consequently, the expansion of the spring and accompanying movement of the sleeve out of the housing causes retraction of the starter gear on the sleeve.

4. The end of the starter gear entering the flywheel gear may be angled or otherwise designed according to the requirements of the flywheel gear, to avoid clashing.

5. Splashing of oil on the threaded sleeve, due to leaks from the rear bearings or otherwise, does not retard and has no other effect on the starter gear in entering the flywheel gear, because of the absence of the usual drag pin that retards the starter gear when there is oil or grease on the threaded sleeve.

6. The durability of the device is considerably improved by the absence of any parts anchored to one another by screws or bolts. All the parts being in this sense independent of each other,

there is nothing to loosen or break under strain.

7. The avoidance of delay and excessive high speed in the meshing of the starter gear with the flywheel gear, as previously described, removes

5 the general cause of breakage of flywheel teeth. Sticking of a starter is due to binding of the starter gear on broken flywheel teeth, and this difficulty is overcome in the present invention by removing the cause of broken teeth.

10 Although a specific embodiment of the invention has been illustrated and described, it will be understood that various alterations in the details of construction may be made without departing from the scope of the invention, as indicated by
15 the appended claims.

What I claim is:

1. In a starter of the class described, a starter drive shaft, an externally threaded sleeve slidable thereon, a starter gear threaded on said sleeve, a spring at one end of said sleeve and adapted to be placed under load on turning of said sleeve within said gear during meshing action of said gear, a stop directly on said shaft and engageable by the other end of said sleeve and by said gear for limiting the movement of said sleeve and gear in one direction, and a spring-backed stop at the first named end of said sleeve for limiting movement of said gear in the other or demeshing direction, said gear being engageable with said spring-backed stop while in threaded engagement with said sleeve, whereby said spring-backed stop exerts pressure on said gear towards the first named stop and against the threads of said sleeve.

35 2. In a starter of the class described, a starter drive shaft, a threaded sleeve slidable thereon, a starter gear threaded on said sleeve, said gear having a chamber therein, a quantity of mercury disposed in said chamber, a baffle in the form of
40 a serrated plate between the inner and outer walls of said chamber and dividing said chamber into

pockets, said plate having ports connecting said pockets, a stop for limiting movement of said gear on said sleeve in one direction, and a spring adapted to be placed under load on turning of said sleeve within said gear.

5

3. In a starter of the class described, a starter drive shaft, a threaded sleeve slidable thereon, a starter gear threaded on said sleeve, a weight carried by said gear, a housing fixed on said shaft, another housing formed on said sleeve between said gear and the fixed housing and having a sliding connection with said fixed housing, a pressure spring within and bearing against said housings, and a stop for limiting movement of said gear on said sleeve in one direction.

15

4. In a starter of the class described, a starter drive shaft, a threaded sleeve slidable thereon, a starter gear threaded on said sleeve, a stop for limiting movement of said gear on said sleeve in one direction, a spring adapted to be placed under load on turning of said sleeve within said gear, a gear retaining sleeve slidably mounted on the first sleeve and positioned to limit movement of said gear in the other direction, and a spring backing said retaining sleeve and adapted to exert spring pressure on said gear towards the first named stop.

20

5. In a starter of the class described, a starter drive shaft, a threaded sleeve slidable thereon, a starter gear threaded on said sleeve, a housing fixed on said shaft, another housing formed on said sleeve between said gear and the fixed housing and having a sliding connection with said fixed housing, a pressure spring within and bearing against said housings, a gear retaining sleeve slidable on the second named housing, and a spring on the last named housing and holding said retaining sleeve under pressure against said starter gear.
